Des. 206,444
Patented Dec. 13, 1966

206,444

CHRISTMAS TREE ORNAMENT

Dario Moranduzzo, Via Aretina 161, Firenze, Italy

Filed Oct. 24, 1965, Ser. No. 87,897

Term of patent 14 years

(Cl. D29—1)

Fig. 1

Fig. 2

Fig. 3

Fig. 4

FIG. 1 is a front elevational view of a Christmas tree ornament showing my new design;

FIG. 2 is a rear elevational view thereof;

FIG. 3 is a top plan view; and

FIG. 4 is a bottom plan view thereof.

The stippled area indicates an enclosed foam ball.

I claim:

The ornamental design for a Christmas tree ornament, as shown and described.
